DESIGN FOR A LIPSTICK CASE

Clara F. Harris, Kansas City, Mo.

Application May 1, 1939, Serial No. 84,705

Term of patent 14 years

To all whom it may concern:

Be it known that I, Clara F. Harris, a citizen of the United States, residing at Kansas City, in the county of Jackson and State of Missouri, have invented a new, original, and ornamental Design for a Lipstick Case, of which the following is a specification, reference being had to the accompanying drawing, forming a part thereof.

Fig. 1 is an elevational view of the lipstick case, showing my design.

Fig. 2 is an elevational view of the lipstick case, turned through 90° from the position shown in Fig. 1; and,

Fig. 3 is an end elevational view thereof.

I claim:

The ornamental design for a lipstick case, as shown.

CLARA F. HARRIS.
